SIGNORS OF ONE-THIRD TO ROBERT D. PEARSON, OF LOS ANGELES, CALIFORNIA

GAS BURNER

Application filed June 19, 1929. Serial No. 372,196.

This invention relates to a rotary burner particularly adapted to move through the atmosphere the flame produced by the burning gaseous fuel, in such a manner as to burn a maximum amount of the atmospheric oxygen.

An object of the invention is to provide an exceedingly simple and dependable appliance of the character stated, one that can be manufactured at a low cost, and that may be used a long time without wearing out or needing to be repaired.

Another object is to provide a burner adapted to function as stated, in which the rotating burner member is furnished with a superior anti-friction mounting means.

A still further object is to provide an improved fluid tight working fit between the rotary burner member and the supply conduit which leads thereto.

Yet another object is to provide a burner particularly well adapted to expand by heat, rings or like circular metal objects in order that they may be shrunk in place upon metallic parts upon which they are to be mounted.

When the device is used for burning oil it will be necessary to deliver the oil through the burner by pressure means sufficient to secure delivery in enough quantity to produce the desired amount of combustion.

Other objects and advantages may herein-after appear.

Referring to the accompanying drawings, which illustrate what is at present deemed to be a preferred embodiment of the invention,

Figure 1 is a vertical mid-section of the complete appliance.

Figure 2 is a plan view thereof, portions of the heat-radiating member being broken away to contract the view.

Figure 3 is a fragmental plan view of a modification.

Fig. 4 is a fragmental view, partly in ele-

vation and partly in vertical mid section, of the modification shown in Fig. 4.

Fig. 5 is a section on line 5—5 of Fig. 3.

Referring in detail to the drawings, the rotary burner head 5 is provided with a plurality of tubular, radially extending burner arms, two such arms, 6 and 7, being shown in the drawings. Said burner head 5 is also of a tubular form, being provided with a chamber or passage 8 the upper portion of which is in communication with the burner arms 6 and 7, and which receives the fuel through the outlets 9a of pivot pipe 9. Owing to the fuel feed openings 9a being led from said pipe 9 in an end-wise manner, it is possible to provide a working fit between said pipe and the tubular burner head 5 without interfering with the flow of the fuel to said burner head.

Said pivot pipe 9 is secured to the tubular standard 10 by means of a fitting or coupling member 11 which is provided at its upper end with a central screw threaded bore into which the lower end of pipe 9 is screwed, and which has at its lower end an externally screw threaded extension 12 whereby it is screwed on to the upper end of standard 10.

Said fitting 11 has an outwardly directed flange 13 upon which is seated the concavo-convex heat radiating member 14. The upper end of coupling 11 is provided with an externally screw threaded portion 15 upon which is screwed the lower end of a dome-shaped housing 16 which forms a combined guide and keeper for the burner head 5 during the rotation of said head. Said housing 16 is provided with a circular opening 17 in its upper end which fits loosely around the lower portion of burner head 5.

The lower end of burner head 5 is provided with an out-curved circumferential flange 18 the lower surface of which contacts rotatably with a convexity 15a of coupling member 11. Against the concavity formed by the upper side of said flange 18 rest a series of ball-

bearing members 19, said ball-bearing members being held in place by the upper contracted portion of the dome-shaped housing 16, which cooperates with the flange 18 to form a cage for said ball-bearing members.

5 A circular guard plate 20, in the form of a collar, is mounted upon the burner head 5 above the housing 16, said plate being provided with a downwardly extending skirt or 10 flange 20a. Contained beneath said collar and flange is a leather or fabric guard 21 which is held in place by a clamping nut 22. Said guard 21 not only keeps dust and dirt out of the bearings, but is also of some value 15 in preventing the escape of gas. The lower portion of said guard moves lightly over the upper portion of the dome-shaped member 16 during rotation of burner head 5.

20 The outer portion of each burner arm 6 and 7 is provided with an apertured portion having an aperture 25 and a deflected portion 26, said aperture 25 and said deflected portion 26 being so constructed and arranged as to direct the issuing fuel tangentially to rotate said burner head. Each aperture or fuel vent 25 is formed as a narrow slit the length of which is directed at right angles to the plane of rotation of the burner head, the fuel vent of the arm 6 being directed 25 oppositely to that of the arm 7.

25 The outer end portion of each of the burner tubes is flattened so as to form, as seen in side elevation, a head *h*, and this gives room to provide a relatively long burner opening 25, 30 this burner opening being formed by cutting away the outer end portion of one side of the flattened portion of the arm. The portion 26 of said arm opposite to this cut-away part is deflected as shown, in order to aid the issuing 35 fuel to react effectively upon the atmosphere and produce a rapid rotation of the burner head together with its arms 6 and 7.

The standard 9 is shown screwed into a well known gas fixture G having a gas faucet 27.

40 Pivot tube 9 is provided at its upper end with an axial, diametrically contracted extension 9b, of considerably less diameter than chamber 6, the upper end of which is pointed and bears against the lower concave end 45 of adjustable bearing screw 9s which is screwed into the upper end of the burner head 5. 9n is a lock nut to keep said screw from working loose.

45 Figs. 3, 4 and 5 illustrate a modification wherein the coupling member 11 and housing 16 of Fig. 1 are combined to form a single supporting member 30 for the rotary head 5x, said member 30 having a pivot pipe 9x screwed thereto whereon said head 5x rotates. This pivot pipe 9x is provided with an external circumferential groove 35 having ports 36 which lead from said groove to the interior of said pivot pipe. The rotary head 5x is provided with tubular arms 6x and 7x 50 which register with groove 35 and therefore

obtain a continuous fuel supply therefrom. The top screw 9y is screwed directly into the upper end of tube 9x, and by the aid of the washer 9w holds the rotary head 5x in place.

55 The heat radiating element 40 is secured by means of screws 41 to a flange 42 with which the member 30 is provided. 10x designates the standard or fuel supply pipe.

60 The fuel feeding arms 6x and 7x as best shown in section in Fig. 5, are each provided with a jacket 45 which, as seen in cross section is provided with a rear taper 46 and front taper 47 to diminish the resistance of the atmosphere to the rapid rotation of the burner head, and to reduce agitation of the 65 atmosphere within the circular path of the flame.

70 The form of the invention last described is intended more particularly for use by jewelers, watchmakers and other artisans requiring a small appliance, while the form first described is deemed preferable for use in expanding large metallic rings and for heavy 75 mechanical work. Medium sized heaters will be used for cooking and house heating.

80 In both forms of the invention the heat radiating element (14 or 40) houses the rotating burner arms sufficiently to form a combustion chamber.

Claims:

1. In a burner, a rotary burner head comprising a tubular body one end of which is closed and the other end of which is provided with an out-curved circumferential flange, means operatively to support said head and to feed fuel thereto under pressure, said means comprising a standard juxtaposed to the flanged end of said head and a pivot pipe over which said head is rotatably fitted, a dome shaped housing mounted upon said standard and inclosing said flange in spaced relation thereto, and ball bearings contacting on one side with the interior of said housing and on the other side with the concave side of said outcurved flange, said housing and outward curved flange cooperating to form a cage for said ball bearings.

100 2. In a burner, a rotary burner head comprising a tubular body one end of which is closed and the other end of which is open, a stationary tubular support for said burner head having a working fit within the lumen of said tubular body, said support having fuel feed vents leading therefrom in an end-wise manner to supply fuel to said burner head and having a reduced extension directed towards the closed end thereof, and a pivot screw adjustably mounted in the closed end of said burner head and having an anti-friction operative relation to said extension.

110 3. In a burner, a rotary burner head having a plurality of tubular radially extending burner arms each of which is provided with a burner aperture, the apertured portions of said arms being constructed and arranged to
